J. R. Judd

UNITED STATES PATENT OFFICE.

JOHN R. JUDD, OF NEW YORK, N. Y.

EXERCISING-MACHINE.

SPECIFICATION forming part of Letters Patent No. 231,431, dated August 24, 1880.

Application filed May 1, 1880. (No model.)

To all whom it may concern:

Be it known that I, JOHN R. JUDD, of the city, county, and State of New York, have invented certain new and useful Improvements 5 in Exercising-Machines, of which the following is a specification, reference being had to the accompanying drawings, forming part of the same.

Figure 1 is a side elevation of a machine 10 containing my improvements. Fig. 2 is a rear view of a portion of the same. Figs. 3, 4, 5, 7, and 8 are detailed views of detached parts, to be particularly described; and Fig. 6 represents the sliding seat and the rails on which 15 it runs.

My invention relates to that class of exercising-machines whereby is provided the opportunity for the employment of muscular force in raising and lowering a weight attached to 20 a cord running over a pulley; and the peculiarity of my invention is, that the mechanism I employ is adapted to be at pleasure readily attached to and detached from the door-case or window-frame of a room, and when 25 detached its several parts, being separated and occupying but little space, may be all conveniently packed in a box or put out of the way.

A is a pulley having its bearing in a bracket, A'. A² is a plate. The opposite side edges 30 are provided with dovetail flanges. The foot of the bracket A', which is a plate with bevelled edges, is fitted to slide in between the said flanges on A² and form a dovetailed joint. The two plates may be slightly and correspondingly tapering. This pulley is designed 35 to be placed near the upper top of the door-case or window-frame of a room by firmly securing the plate A² to the under work by screws, as shown in Fig. 1. B is another pulley, having 40 its bearings in a bracket, B'. This is intended to be secured to the floor in a manner similar to that by which A is secured to the door-case—namely, by a plate, B², having flanges at its sides, into which the foot of the 45 bracket fits with a dovetailed joint. When the plate B² is secured to the floor, as seen in Fig. 1, and the bracket is slid into its seat between the dovetail flanges, it is locked in place by a swinging bar, a, (hinged to the plate 50 B²), that is swung over and dropped down behind the rear end of the foot of the bracket.

C is the rope which runs over the pulley A and under the pulley B, with its end b connected to a rod, b', to the lower end of which is attached a block, b², constituting a weight to be 55 lifted by pulling at the opposite end of the rope, which is furnished with a handle, b³, for the purpose. Additional weights may be laid on blocks b².

D D' are guide-rods for steadyng the weight 60 b² as it rises and falls. These rods are provided with eyes d d' d² d³ at their ends, by which they are hooked onto hooks d⁴ d⁵ d⁶ d⁷. The hooks d⁴ and d⁵ may be screwed into the floor of the room, but preferably attached to 65 the plate B², in which is held the bracket B'. The shanks of the hooks d⁶ and d⁷ are screw-threaded and provided with thumb-nuts. They are held in slotted openings in arms e e', that extend from the center of the bracket A'. The 70 rods D D' may be adjusted in place by hooking their lower ends onto the hooks d⁴ and d⁵ and the upper ends into the hooks d⁶ d⁷, and then slipping the latter into the nuts in the arms e e' and turning down the thumb-nuts. 75 The rods may be detached, obviously, by reverse movements. If preferred, d⁶ and d⁷ may be simply eyebolts permanently connected with the eyes in the rods, or the eyes in the upper ends of the rods D D' and the hooks d⁶ 80 and d⁷ may be dispensed with, and the said rods provided at the upper ends with screw-threads and thumb-nuts, and placed in the slotted openings in the arms e e'.

The block b² is provided with ears f f', Fig. 85 7, which extend laterally from it, and through which pass the rods D D'. These ears are preferably made of thick rawhide and held in recess in the top face of the said block.

The holes f² f³ for the rods should be slotted 90 out to the end of the ears, the slots being cut at an angle to the axis of the holes. The rods may then be passed through the slots into the holes by flexing the sides of the slots, whereby, when the rods are in the holes and the sides 95 of the slots are bent back to a plane, the rods are held from moving back into the slots.

The block b² and the several weights may be raised in their upper face, with projections on their lower face to fit into the recesses to prevent them sliding one upon another.

E E' are ways upon which a sliding seat, E²,

is arranged to run. Preferably they are simply the upper edges of the sides of a box, as shown in Fig. 6. They should be made of hard wood, of sufficient thickness for the purpose, 5 provided with grooves $g\ g'$. The seat may be provided with ribs on its under face fitting into the said grooves.

F is a bar pivoted at one end to the end of the box G, and at the opposite end provided 10 with a downwardly-extending arm, h, having a hook, h' , to hook into an eye, h^2 , in the foot of bracket B'.

H is a foot-rest, which may be of any suitable material. It is suitably formed, being preferably 15 two shoes connected by a cross-bar to receive the feet of the operator, one end resting on the floor and the other supported on legs extending from the sides of the bracket B', the rest being provided with slotted ears or 20 hooks i, to hook onto the said lugs, so as to give the rest the proper inclination, as shown in Fig. 1. The rest, if preferred, may be connected to the bar F, as shown in the dotted lines in said Fig. 1. The connection is made 25 by arranging the ears i to project down one on each side of the said bar, the foot-rest being divided at the top to admit the bar between the divisions. A bolt passing through the lugs and bar will attach them together; 30 then, by having several holes in the bar, the foot-rest may be adjusted at pleasure in relation to the seat E².

It is obvious that the several posts of the apparatus here described are all readily detachable from each other and from the side of 35 the room, to which the brackets A' and B' are to be attached when arranged for use. The dovetail plates A² and B² are designed to be permanently screwed, the former to the side

of the door-case of a room, or some other convenient place on the wall, and the latter to the floor. Then the brackets may be readily connected with and detached from said plates, and the other parts connected and disconnected at pleasure, as hereinbefore described. The 45 whole may be, if desired, placed within the box G, or otherwise used in a small space, out of the way when not in use, and may quickly and conveniently be put up and arranged for use. This enables any person to have in his 50 sleeping-apartment, if he desires, an exercising-machine that is not an incumbrance or inconvenience.

What I claim as new, and desire to secure by Letters Patent, is—

1. A detachable exercising-machine, composed of the pulleys A B, brackets A' B', dovetail plates A² and B², rope C, rod b', and block b², as and for the purpose described.

2. The combination, with the brackets A' 60 and B' and pulleys A B, of the detachable rod D D' and the block b², as and for the purpose described.

3. The combination, with the brackets A' and B', pulleys A B, rope C, block b², and foot-rest 65 H, of the ways E E' and sliding seat E², connected to the brackets B' by the detachable bar F of the adjustable foot-rest H, as and for the purpose described.

4. The combination, with the bracket B', of 70 the pulleys, rope, and weight of the seat E², ways E E', and detachable bar F of the adjustable foot-rest H, as and for the purpose described.

J. R. JUDD.
